UNITED STATES PATENT OFFICE.

FRANK MAMMI, OF BROOKLYN, NEW YORK.

DESIGN FOR A RADIATOR FACEPLATE.

Application filed May 4, 1926. Serial No. 17,565. Term of patent 14 years.

To all whom it may concern:

Be it known that I, FRANK MAMMI, a citizen of the United States, residing in Brooklyn, county of Kings, and State of New York, have invented a certain new, original, and ornamental Design for Radiator Faceplates, of which the following is a specification, reference being had to the accompanying drawings, forming a part thereof, and of which—

Figure 1 is a front elevation, and Fig. 2 is a vertical section of the same on the line 2—2 of Fig. 1, of a radiator face plate showing my new design.

I claim:

The ornamental design for a radiator faceplate as shown.

FRANK MAMMI.
